RECIRCULATING RADIATOR SYSTEM

Frederic W. Hild, Los Angeles, Calif.

Application January 13, 1948, Serial No. 2,121

16 Claims. (Cl. 123—41.45)

1

This invention relates to cooling systems for internal combustion engines and particularly to the radiators thereof, and is an improvement of the system described in my co-pending application Serial # 577,302 filed February 5, 1945, now Patent Number 2,435,041, January 27, 1948, for Regulating Device for Cooling System.

It is well understood that with the conventional radiator for auto vehicles, the heated water from the engine enters the hot water tank at the upper part of the radiator, flows downward therefrom through small water passages in the cooling core where it is cooled by the forced draft of atmospheric air moving through air passages approximately at right angles to the water movement, the air being drawn through the core by the engine driven fan. The cooled water enters the lower tank discharging therefrom and is circulated by the engine driven water pump through the engine cooling channels and the radiator.

The objective function of the radiator is to cause the maximum difference of temperature between the hot water entering the upper tank and the cooled water flowing from the lower tank.

When the cooling air moves through the core thermal interchange results in cooling the water and heating the air. The heating of the air increases very rapidly as it passes through the core due mainly to the absorption of heat from the circulating water. As a result the practical effective thickness of the core is quite limited.

It follows that the streams of water descending the water passages at and near the front of the cooling core are subjectd to much greater cooling by the air and therefore become much cooler as they descend than the similar streams at or near the rear part of the core.

It is an object of this invention to utilize the difference of the temperatures of the descending water streams by providing the radiator with two or more receptacles adapted to separate and contain the water streams from the cooling core according to the said different temperatures, and to provide separate outlets for said receptacles.

Another object is to further improve the radiator and its operation by providing in the radiator a simple recirculating device without a moving part, adapted to cause a substantial portion of the radiator water to by-pass the engine and recirculate continually through the entire radiator.

It is another object of this invention to make it possible to utilize a smaller radiator than has been necessary, and yet produce equivalent cooling.

It is generally recognized that to attain the best efficiency and most economical operation, the engine temperatures should be maintained within a comparatively narrow range of quite high temperatures representing and being the optimum range.

2

Thus engine operating temperatures below the low point of the optimum range means underheat operations and this as well as overheat operation means diminished engine power, waste of fuel, increased maintenance.

In the present prevailing cooling systems, a single thermostat valve in the outlet of the cylinder jackets, is relied upon to regulate the temperature of the jacket water. This thermostat valve operates to by-pass the entire radiator until the jacket water attains a predetermined hot temperature whereupon the valve opens to admit cold radiator water into the cylinder jackets.

This predetermined hot temperature is usually much lower than the lowest temperature of the aforesaid optimum range and manifestly until optimum temperature is attained the engine runs underheated.

Added to this, the wide range of weather temperatures, the variable and intermittent engine loads, the frequency of cold starting—all these combined result in most automotive engine operation being underheated operation.

It is an object of the present invention to provide radiator means adapted to maintain far more closely and for longer periods the desired optimum range of engine operation temperatures and thereby virtually prevent underheat and overheat engine operation.

Another object of the invention is to provide a radiator which includes a jet condenser and thereby reduce vaporization of overheated liquid from the engine, conserving said liquid and additionally contribute toward preventing overheat operation.

This invention possesses other advantages and has other objects which will become apparent from consideration of the drawings and the accompanying description.

40 Referring to the drawings:

Figure 1 shows in diagram an embodiment of the invention in the cooling system of an automotive engine, the lower tank being shown in open horizontal plan, and all other members in vertical elevation;

Fig. 2 is a vertical section of the improved radiator showing the recirculator therein;

Fig. 3 is a sectional view of the lower tank of the radiator taken on the line 3—3 of Fig. 2;

50 Fig. 4 is a fragmentary view of one end of the interior of the lower tank showing a flow opening therein;

Fig. 5 is a part section of the upper portion of the radiator showing a thermostat valve in the recirculator; and

Fig. 6 shows in diagram an embodiment of the invention in a cooling system having a separate member serving as a jet condenser for cooling heated water from the engine.

60 In the drawings beginning with Figures 1-2-3 and 4, the radiator 10 is air cooled by the fan 11

which is driven by the engine 12 in the usual way.

The engine also drives the water pump 13 for circulating cooling liquid through the cooling channels of the engine and the radiator.

The radiator 10 comprises the cooling core 14, the upper receiving tank 15, the lower reservoir tank 16, and the recirculator 17, which provides two inlets 18 and 19 respectively for tank 16.

For replenishing the water supply the radiator had the usual opening and closure cap at the top of the receiving tank, also the usual overflow pipe therefor.

The cooling core 14 may be of the conventional honeycomb, cellular or tubular types or any other suitable type that has water passages and air passages disposed at substantially right angles to each other, the water passages leading downward from the upper tank to the lower tank. The front and rear halves of the core designated herein as 14F and 14R respectively, function as two separate cores.

The recirculator 17 comprises the jet pump 20 and the discharge bowl 24, both being secured to the tank 15 and to each other. The jet pump 20 has the usual nozzle 21 discharging through its small end into a constricted passage 22 forming the venturi and surrounded by the usual vacuum chamber 23 which is also adapted to discharge into passage 22. The liquid flowing through passage 22 enters the discharge bowl 24 discharging therefrom into the receiving tank 15. The discharge opening of bowl 24 is higher than the water level in the vacuum chamber for a reason later explained.

The discharge bowl 24 is wholly within the tank 15. The bowl has neck 25 and flange 26 for permanently securing the bowl to the tank wall.

The jet pump 20 is removably secured to the bowl by means of its passage 22 which fits into neck 25 of the bowl and by jet pump flange 27 which is securely bolted to the tank wall and flange 26 of the bowl.

The large end of nozzle 21 serves as inlet 18 and is connected by pipe 28 to the usual thermostat valve 29 in the outlet of the engine cylinder jackets. The vacuum chamber 23 of the recirculator has the aforesaid inlet 19 for receiving liquid from the lower tank 16.

The thermostat valve 29 may be either the single outlet type or the two outlet type, both of which have long been in use in automotive engines and are well known so that detail of their construction is not shown.

If the valve 29 be the single outlet type then when the valve is closed the water merely churns with slight or no circulation in the cylinder jackets.

In Figures 1 and 6 the valve 29 has two outlet ports, one being connected to pipe 28 and the other to flow passage 28A. Flow passage 28A comprises a channel within the engine (shown by the broken lines) and a tubular connection to the suction end or inlet of pump 13.

When the thermostat valve 29 closes the outlet to pipe 28 then the flow passage 28A is open and the water circulates through pump 13 and the cylinder jackets of the engine, by-passing the entire radiator. When the valve closes flow passage 28A, then the circulation flows through pipe 28.

The lower tank 16 comprises two receptacles 30 and 31 respectively which may be separated as by the hollow partition 32 so that liquid can flow from one receptacle to the other only through opening 33 in a lower corner of the partition.

The open ends 34 of the partition enable free movement of air through the hollow interior of the partition thereby providing air insulation between the receptacles.

5 The two receptacles divide the water passages of the cooling core 14 into the two cores 14F and 14R so that the front receptacle 30 receives from 14F the water which is most effectively cooled.

10 The receptacles 30 and 31 may be separate receiving tanks, each exposed to atmosphere on all sides. In either case the water in a front receptacle is always cooler than the water in the next rear receptacle.

15 A tube 35 which extends from the front receptacle 30 through the rear receptacle and the rear side of the lower tank, forms the outlet for the front receptacle and discharges liquid therefrom through pipe 36 into the suction end of pump 13. The pump discharge flows through 20 pipe 37 into the inlet of the engine cooling jacket. An outlet 38 from the receptacle 31 leads cooled liquid therefrom into pipe 39 and thence into inlet 19 of the recirculator 17.

25 In the present instance, as in the conventional system, the valve 29 opens flow passage 28A and closes the outlet to pipe 28 during the period of cold starting and underheat operation and until a predetermined temperature designated Temp A, is attained. The coolant then circulates only 30 through the water pump and the engine cylinder jackets and by-passes the entire radiator. This may be termed "Engine short path."

35 Because the short path and the comparatively small quantity of water thus circulated without benefit of forced cooling, Temp A may be reached from cold start in fairly short time during warm weather conditions, but longer time is required during cold weather.

40 In the conventional system when the valve 29 closes flow passage 28A and opens pipe 28, the circulation through the cooling system may be designated "Long single path."

45 In the system shown by Figure 1 and radiator 10 when thermostat valve 29 closes flow passage 28A, heated water at Temp A under pressure of water pump 13 flows from the engine cylinder jackets through pipe 28 into the recirculator 17 at inlet 18 and into jet pump 20. The water flows rapidly through nozzle 21 into constricted passage 22 and creates a vacuum in chamber 23. Thereupon, the vacuum causes cooled water to flow from the rear receptacle 31 through outlet 38, pipe 39, inlet 19 and into the vacuum chamber 23. This cooled water mingles with the hot jacket water as both streams flow through the passage 22 into discharge bowl 24 and then into the water passages of the cooling core.

50 The vacuum induced stream by-passes the engine and is not subjected to the intense heat in the cylinder jackets. Its path through pipe 39 and through the radiator is much shorter than the positive pressure stream circulating through the pump 13, the engine cylinder jackets and the radiator. Thus, the portion of the cooled radiator water moving because of the vacuum in recirculator 17, circulates through the cooling cores 14F and 14R with greater frequency and is subjected to much more cooling than the aforesaid positive pressure stream.

55 Manifestly this cooled water from the lower tank reduces the temperature of the hot engine water in the recirculator 17 before the combined streams flow therefrom into the cooling core. Thus the water flowing downward through all of 70 the cooling core 14 and received by receptacles 30

and 31 is very much cooler than if there had been no recirculation of the radiator water as described.

Moreover this precooling of the heated water in the recirculator 17 diminishes vaporization and thereby conserves the cooling water. Thus the upper tank 15 and the jet pump 20 serve also as a jet condenser.

The circulation described may be designated "Recirculator double path" circulation.

The level of the water issuing from the discharge bowl is higher than the level of the water in the vacuum chamber. Therefore even though the water supply in the radiator falls very low, nevertheless the vacuum induced water flow will not be interrupted.

Thus the radiator embodying the invention herein described operates to supply water that is very much cooler than is possible with the conventional radiator. Hence the improved radiator in effect is equivalent to a larger conventional radiator of larger water capacity.

Figure 5 shows the radiator 10A provided with the thermostat valve 40, which is removably secured in the discharge bowl 29 of recirculator 17, by a suitable packing 41 and a breech locking plate 42. The thermostat valve may be lowered and removed through a top opening 43 of the radiator which has a closure cap 44 therefor. Otherwise the radiator 10A is the same as radiator 10.

Radiator 10A provides an important improvement of the cooling system described in the aforesaid co-pending application Serial #577,302, now Patent Number 2,435,041, January 27, 1948, in which is shown that:

The Temp A setting of thermostat valve 29 may closely approximate the low temperature point of the aforesaid optimum range. The thermostat valve 40 may be set to open at a temperature designated as Temp B which should closely approximate the high temperature point of the optimum range.

During the time thermostat valve 29 closes pipe 28 the circulation follows the previously described conventional engine short path.

Upon the jacket water attaining Temp A, the thermostat valve 29 closes flow passage 28A and opens to pipe 28, but thermostat valve 40 remains closed. Therefore heated water from the engine jackets, moving under the pressure of pump 13, flows into chamber 23 of recirculator 17, thence downward through pipe 39 into rear receptacle 31 of lower tank 16, then longitudinally through said receptacle through opening 33 of partition 32, and longitudinally through front receptacle 30 into outlet 35 and thence into the suction end of pump 13. The two receptacles 30 and 31 in series form a cooled water channel that is longer than the water passage through the cooling core of the radiator.

Thus the heated circulating water by-passes both the upper tank and the two cooling cores of the radiator, but during its prolonged passage through the cooled water in the two receptacles, thermal exchange occurs, resulting in the circulating water losing much of its heat. At the same time the water thus heated in the receptacles rises upward by convection into the two cooling cores, 14F and 14R where it is cooled by the forced air draft through the cores.

Simultaneously cold water from the front receptacle 30 flows into the hot cylinder jackets and lowers the temperature of the water therein so that valve 29 may move to open and close

intermittently as the heat in the cylinder jacket increases.

This circulation may be designated "lower tank path."

When heavier and hotter operating conditions cause the water surrounding the thermostat 40 to attain Temp B, then the valve 40 opens. Thereupon the water circulation follows "Recirculator double path" previously described for radiator 10.

The three circulating paths together with the other improvements and advantages herein described, manifestly provide much greater latitude and flexibility of control and regulation of the engine temperatures than the present prevailing cooling system.

A certain minimum quantity of water in the radiator is essential for proper functioning, otherwise the engine will run too hot and overheat operation will be increased. Also in the prevailing cooling system the radiator water must not exceed a certain specified maximum quantity, otherwise the engine would run too cold and the underheat operation would be increased.

Radiator 10A with the recirculator 17 and the thermostat 40 and the other improvements herein described, eliminates the restrictions and limitations as to maximum water quantity and enables the use of larger cooling water capacity whether in a larger radiator, or with an additional auxiliary supply in a separate container. This obviously provides the required minimum quantity of water and overheat operations can be virtually eliminated.

Moreover with radiator 10A the engine temperatures can be held far more closely to the desired optimum range than is possible with the present prevailing cooling systems. Thus except for the brief period of cold starting, underheat operation can be reduced so much as to be practically negligible.

Referring to Figure 6, this shows engine 12 and water pump 13 in circulatory connection with radiator 45 and condenser 46.

The upper tank of radiator 45 has inlet 48, filler cap 51 and an overflow pipe which has small valve 52. When this valve is open, the level of the coolant in the radiator is as in the usual radiators. The recirculator 17 with thermostat valve 40 is omitted from radiator 45 and placed partly in condenser tank 46. In all other respects the radiator 45 is the same as radiator 10. The outlet 35 of the front lower tank of the radiator is connected by pipe 36 to pump 13 which discharges through pipe 37 into cylinder jackets of the engine.

The condenser 46 comprises a tank the top of which has air breather tube 50 which also may be used as coolant overflow pipe. A removable closure cap 49 normally closes a top opening which may be used for replenishing the coolant supply of the cooling system; also the thermostat 40 may be passed through said opening.

Upon closing the small valve 52 of the radiator 45 the condenser tank may serve as an auxiliary container of coolant in addition to that in the radiator.

An outlet in the bottom of the tank is connected by pipe 47 to radiator inlet 48. The condenser tank has the recirculator 17 and thermostat valve 40. The inlet 18 of the recirculator is connected by pipe 28 to thermostat valve 29 in the outlet of the cylinder jackets. The inlet 19

of the recirculator is connected by pipe 39A to radiator outlet 38.

When valve 29 opens to pipe 28 and valve 40 is closed, the circulation flows from the engine jackets into chamber 23 of the recirculator and thence downward through pipe 39A into and longitudinally through the two lower tanks of the radiator and into pump 13 and the cylinder jacket. The circulation follows the previously described "Lower tank path" and may be so designated for the system of Fig. 6. This circulation by-passes the condenser tank, the upper tank and cooling core of the radiator.

When valve 40 opens at Temp B which is below the boiling point of the circulating liquid, the heated water flows into jet pump 20, creating negative pressure in the vacuum chamber 23 of the jet pump which causes cooled water to flow from the rear lower tank into said chamber, the cooled water mingling with the hot water in said chamber, the mingled stream at lower temperature issuing from the discharge bowl of the recirculator 17 into the condenser tank 46 then flowing therefrom through inlet 48 into the upper tank of the radiator 45 and down the cooling core into the two lower tanks.

The water thus cooled, divides on leaving the lower tank: Part of it flows to the pump 13, and through the cylinder jackets and into the recirculator 17; the remainder by-passes the pump and the engine and flows directly into the recirculator. Thus the condenser 46 with the recirculator 17 operates as a jet condenser for precooling steaming overheated water and suppressing vaporization of said water prior to its circulating through the radiator.

The circulation when valve 40 is open may be designated "Condenser double path circulation."

Although several specific embodiments of the invention have been described herein, it will be understood that various other forms and modifications may be made without departing from the spirit or scope of the invention herein described or the principles herein set forth.

The inventor claims:

1. In a cooling system for use with a water jacket of an internal combustion engine: a radiator having an upper tank, a lower tank and cores connecting the tanks; a connection between the lower tank and the water jacket; a connection between the upper tank and the water jacket; means for creating pressure to pass a coolant from the lower tank to the jacket; means for passing additional coolant from the lower tank to the upper tank; said additional coolant by-passing the water jacket; and a temperature responsive valve means controlling said by-passing means.

2. In a cooling system for use with a water jacket of an internal combustion engine: a radiator having an upper tank, a lower tank and cores connecting the tanks; a connection between the lower tank and the water jacket; a connection between the upper tank and the water jacket; means for creating pressure to pass a coolant from the lower tank to the jacket; a first valve controlling egress of coolant from the water jacket; a second valve controlling the passage of coolant through said first valve into the upper tank; a by-pass connection between the lower end of the tank and the intake side of said second valve; means responsive to temperature of the coolant at the first valve for opening said valve at a temperature corresponding to the lower limit; and means responsive

to temperature of the coolant at the second valve for opening said second valve at a temperature corresponding to a higher limit.

3. In a cooling system for use with a water jacket of an internal combustion engine: a radiator having an upper tank, a lower tank and cores connecting the tanks; a connection between the lower tank and the water jacket; a connection between the upper tank and the water jacket; means for creating pressure to pass a coolant from the lower tank to the jacket; means for passing additional coolant directly from the lower tank to the upper tank; said additional coolant by-passing the water jacket; and a jet pump adjacent the top of the means for passing additional coolant, to force coolant from the said passing means into the upper tank.

4. In a cooling system for use with a water jacket of an internal combustion engine: a radiator having an upper tank, a lower tank and cores connecting the tanks; a connection between the lower tank and the water jacket; a connection between the upper tank and the water jacket; means for creating pressure to pass a coolant from the lower tank to the jacket; means for passing additional coolant from the lower tank to the upper tank; said additional coolant by-passing the water jacket; a bowl in the upper tank; and a jet pump between the by-pass means and the bowl for forcing coolant from the by-pass into the bowl, said bowl having a discharge opening communicating with the upper tank, the jet pump discharging below the said opening.

5. In a cooling system for use with a water jacket of an internal combustion engine: a radiator having an upper tank, a lower tank and cores connecting the tanks; a connection between the lower tank and the water jacket; means for creating pressure to pass a coolant from the lower tank to the inlet side of the jacket; a supplemental tank; a first conduit between said supplemental tank and the outlet side of the jacket; a second conduit from the lower tank to the supplemental tank; and a third conduit from the upper tank to the supplemental tank.

6. In a cooling system for use with a water jacket of an internal combustion engine: a radiator having an upper tank, a lower tank and cores connecting the tanks; a connection between the lower tank and the water jacket; means for creating pressure to pass a coolant from the lower tank to the inlet side of the jacket; a supplemental tank; a first conduit between said supplemental tank and the outlet side of the jacket; a second conduit from the lower tank to the supplemental tank; a third conduit from the upper tank to the supplemental tank; and a valve responsive to temperature at the jacket outlet for causing flow of the coolant from the outlet.

7. In a cooling system for use with a water jacket of an internal combustion engine: a radiator having an upper tank, a lower tank including a front section and a rear section, and cores connecting the upper tank with the lower tank sections, the front cores communicating with the front section, and the rear cores communicating with the rear section; a first conduit between the front section and the inlet of the water jacket; a second conduit from the outlet of the water jacket to the upper tank; and a

third conduit between the rear section and the upper tank.

8. In a cooling system for use with a water jacket of an internal combustion engine: a radiator having an upper tank, a lower tank including a front section and a rear section, and cores connecting the upper tank with the lower tank sections, the front cores communicating with the front section, and the rear cores communicating with the rear section; a first conduit between the front section and the inlet of the water jacket; a second conduit from the outlet of the water jacket to the upper tank; a third conduit between the rear section and the upper tank; and a jet pump located between the top of the third conduit and the upper tank, for causing coolant to be passed through the third conduit.

9. In a cooling system for use with a water jacket of an internal combustion engine: a radiator having an upper tank, a lower tank including a front section and a rear section, and cores connecting the upper tank with the lower tank sections, the front cores communicating with the front sections, and the rear cores communicating with the rear section; a first conduit between the front section and the inlet of the water jacket; a second conduit from the outlet of the water jacket to the upper tank; a third conduit between the rear section and the upper tank; and a valve at the jacket outlet for permitting flow of coolant through said second conduit, and responsive to attainment of a definite temperature of the coolant at the outlet of the water jacket.

10. In a cooling system for use with a water jacket of an internal combustion engine: a radiator having an upper tank, a lower tank including a front section and a rear section, and cores connecting the upper tank with the lower tank sections, the front cores communicating with the front section, and the rear cores communicating with the rear section; a first conduit between the front section and the inlet of the water jacket; a second conduit from the outlet of the water jacket to the upper tank; a third conduit between the rear section and the upper tank; a jet pump located between the top of the third conduit and the upper tank, for causing coolant to be passed through the third conduit; and a thermal responsive valve controlling the outlet of the water jacket.

11. In a cooling system for use with a water jacket of an internal combustion engine: a radiator having an upper tank, a lower tank including a front section and a rear section, and cores connecting the upper tank with the lower tank sections, the front cores communicating with the front section, and the rear cores communicating with the rear section; a first conduit between the front section and the inlet of the water jacket; a second conduit from the outlet of the water jacket to the upper tank; a third conduit between the rear section and the upper tank; a jet pump located between the top of the third conduit and the upper tank, for causing coolant to be passed through the third conduit; and a bowl in the upper tank into which the jet pump discharges.

12. In a cooling system for use with a water jacket of an internal combustion engine: a radiator having an upper tank, a lower tank and cores connecting the tanks; a connection between the lower tank and the water jacket; means for

creating pressure to pass a coolant from the lower tank to the inlet side of the jacket; a supplemental tank; a first conduit between said supplemental tank and the outlet side of the jacket; a second conduit from the lower tank to the supplemental tank; a third conduit from the upper tank to the supplemental tank; and a valved overflow pipe leading from the top of the upper tank.

13. In a cooling system for use with a water jacket of an internal combustion engine: a radiator having an upper tank, a lower tank including a front section and a rear section, and cores connecting the upper tank with the lower tank sections, the front cores communicating with the front section, and the rear cores communicating with the rear section; said front and rear sections being connected by a passage, and having adjacent walls formed of a hollow open conduit; a first conduit between the front section and the inlet of the water jacket; a second conduit from the outlet of the water jacket to the upper tank; and a third conduit between the rear section and the upper tank.

14. In a radiator: an upper tank; a lower tank having a front section, a rear section, and a double wall between the sections and open at both ends; cores connecting the upper tank with the lower tank; and means forming a port between the sections.

15. In a radiator: an upper tank; a lower tank having a front section, a rear section, and a double wall between the sections and open at both ends; cores connecting the upper tank with the lower tank; means forming a port between the sections; and a connection between the rear tank section and the upper tank.

16. In a cooling system for use with a water jacket of an internal combustion engine: a radiator having an upper tank, a lower tank, and cores connecting the tanks; means for passing a coolant from the lower tank to the water jacket and thence to the upper tank; by-passing means for passing additional coolant from the lower tank to the upper tank, said additional coolant by-passing the water jacket; a bowl having an open top, and disposed in the upper tank; and a jet pump between the by-passing means and the bowl for forcing coolant from the by-passing means into the bowl, the jet pump discharging below the open top of the bowl.
